[57] CLAIM

The ornamental design for a wall or partition hung graphics holder, as shown and described.

DESCRIPTION

FIG. 1 is a reduced perspective view of a wall or partition hung graphics holder showing my new design, the partition, or the like, being shown in broken lines for illustrative purposes only;

FIG. 2 is an enlarged front, top, right side perspective view thereof;

FIG. 3 is a top view thereof;

FIG. 4 is a front elevational view thereof;

FIG. 5 is a bottom view thereof;

FIG. 6 is a rear elevational view thereof;

FIG. 7 is a right side elevational view thereof, the opposite side being a mirror image of the side shown; and FIGS. 8, 9 and 10 are second, third, and fourth embodiments of the design of FIG. 1, wherein the bracket or partition retaining portion of the device is of varying width to accommodate various thicknesses of partitions.
